[Term of Patent 3½ years.]

CASE A.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto forming the base of this design is "God is our Refuge and Strength." The

form of the letters composing the several words are clearly shown in the accompanying illustration, the capitals being the principal feature in this part of the design. The ornamentation around or filling of the pattern is of a floriated character, interlacing the several words or letters, as shown in the accompanying illustration.

I claim—

The design for embroidery-pattern herein described, consisting of the motto "God is our Refuge and Strength," in form and ornamentation as shown in the accompanying illustration.

EMIL CRISAND.
